UNITED STATES PATENT OFFICE.

DANIEL OSCAR FOSGATE, OF AURORA, ILLINOIS, ASSIGNOR TO HENRY B. HARFORD, OF SCOTT COUNTY, IOWA.

BUSTLE.

SPECIFICATION forming part of Letters Patent No. 363,458, dated May 24, 1887.

Application filed October 28, 1886. Serial No. 217,451. (No model.)

To all whom it may concern:

Be it known that I, DANIEL OSCAR FOSGATE, a citizen of the United States, residing at Aurora, in the county of Kane and State 5 of Illinois, have invented new and useful Improvements in Bustles, of which the following is a specification.

My invention relates to improvements in bustles; and the novelty consists in the peculiar construction, arrangement, and adaptation of parts for service, substantially as hereinafter described, and particularly pointed out in the claims.

The object of my invention is the provision 15 of a bustle which can be very easily and securely attached and retained in place, and which shall be very light in weight and also possess sufficient elasticity to "give" or respond to the movements of the wearer, thereby 20 rendering the bustle comfortable.

I attain the above objects by the device shown in the accompanying drawings, which illustrate a bustle constructed in accordance with and embodying the features of my invention, in which drawings—

Figure 1 is a plan view of my improved bustle. Fig. 2 is a side elevation of the same. Fig. 3 is a detail view of one of the side attaching-plates. Fig. 4 is a detached perspective view of the side plates and proximate parts. Fig. 5 is a view of the band for the waist. Fig. 6 is a detached perspective view showing the connection between the springs.

Referring to the drawings, in which similar 35 letters of reference denote corresponding parts in all the figures thereof, A and A' designate metal plates providing the means for attaching the bustle, and which, for the sake of convenience, I will term "attaching-plates."

In describing the invention I shall suppose 40 the device as applied in position, and in using the terms "outer" and "inner" will distinguish with reference to the position of the parts relative to the body, the latter being 45 considered the center, from which the parts of the device extend outward. At the inner end of these attaching-plates are provided horizontal slots a, to allow the passage of a tape or band, B, therethrough. This tape or band out- 50 side the slots is secured to and passed through a cloth covering, B', and extends outward therefrom to any desired length, one end of the tape

or band having a buckle, a'. The cloth covering B' incloses the side attaching-plates, A and A', and the proximate parts. In the opposite or outer ends of these plates are openings a², to receive the hooked ends of a curved wire, C, which is secured to said plates and provides a rest or support for the bustle, confines the skirts, and prevents them from becoming 55 entangled with the bustle. These plates are also formed on the upper side with projecting inclined extensions or arms a³, any number of which may be employed, according to the size of the bustle.

D and D' designate transverse end brace coiled springs, which have their ends coiled around, and thus secured to the first and last of the series of arms a³ of each plate A and A', and intermediate of these end brace coiled springs are a number of transverse coiled springs, E, both the end brace springs and the intermediate transverse springs being curved and spaced apart to give a suitable and proper shape to the bustle, and forming an open 75 spring-frame, as shown.

In the present form of bustle I have shown three arms or extensions, a³, for the plates A and A', and I employ three intermediate coiled springs, the center one of which has its ends 80 coiled around and held to the center arm, a³, and the two others are coiled around the same arm to which the end brace-springs, D and D', are secured. Of course, while the ends of all the transverse springs D, D', and E come close 85 together, their main body portions are spaced apart to provide the necessary supporting and bulged surface to give the proper shape to the bustle.

F designates the curved main coil-spring for 90 retaining the transverse springs in position and yet preserving their elasticity. It is attached at its front ends to the end spring D, carried inward toward the center for a short distance until the two branches of the spring F 95 nearly come together, at which point, a⁵, they are attached to the end spring D, and then outwardly, the two branches of springs F engaging or twisting in each of the transverse coils on opposite sides of the bustle-frame and projecting for a short distance outward beyond and below the end brace-spring D', forming an open loop, as at a⁶.

G and G' designate longitudinal brace-

springs, which have their inner ends secured to the branches of the curved spring F beyond the inner end spring, D, and pass outwardly over the upper portion of the transverse springs, with their coils engaging the coils of said transverse springs.

From this construction it will be seen that I have the coils of all the springs forming the bustle intertwined with or engaging each other, as clearly shown in Fig. 6, thereby providing a bustle in which all the springs, when compressed, will yield at the same time, and which will recoil immediately when released from the compression. It will also be observed that I provide a skeletonized spring-frame in the form of a bustle, in which frame the springs will be connected together and held from independent movement. The springs cannot be moved laterally out of place, since the coils of the springs are intertwined one within the other. The transverse springs D, D', and E fix the shape of the bustle, while the main and brace springs F G mainly serve to hold the transverse springs together and preserve the form of the bustle. The loop a^6 on the main spring serves to taper or round off the bustle neatly in giving the required form. Attached to the waist or attaching band B are loops b and b', through which the curved spring F is adapted to pass. This holds the spring-frame from sagging outward from the body of the wearer.

The sheaths or coverings B', which cover the attaching-plates and conceal them entirely from view, serve to make the bustle neater in appearance, and also protect the clothes from soiling at the points of most direct contact.

From the foregoing description, taken in connection with the drawings, it will be seen that I provide a bustle which can be easily applied and which is always supported in position under all circumstances, which is very light in weight and very elastic, and thereby readily accommodates itself to the positions assumed by the wearer, so that the drapery will always be retained in perfect shape.

Special stress is laid on the attaching-plates A and A', from the fact that they provide for the attachment of the body-wire C, the springs, and the attaching-band.

I am aware that bustles made of coiled springs are not new, and this, broadly, I disclaim.

I lay special stress on the separation of the springs, being curved and spaced apart to give proper shape to the bustle, and all connected together to prevent lateral movement of the springs; also the body-wire C, which serves to confine the skirts adjacent to the bustle, prevents the springs from being entangled with the skirts, and also supports the bustle. It will also be seen that my bustle is very simple in construction and inexpensive of manufacture.

I do not limit myself to the precise construc-

tion of parts described, or to any particular number of wiresprings, as such may be changed to suit the circumstances without departing from the spirit of my invention.

I claim—

1. In a bustle, the herein-described attaching-plates having a series of projecting arms and having slots in their ends, the waist-band passing through the slots, the body-wire attached at its ends to the plates, and the spring bustle-frame having its transverse coils secured to and carried by the arms of said plates, substantially as set forth. 75

2. In a bustle, the attaching-plates, the transverse curved coiled springs attached to said plates, the curved main spring connecting the transverse coiled springs, and the longitudinal brace-springs passing over the upper face of the coiled transverse springs and engaging therewith, as set forth. 80

3. In a bustle, the combination of the attaching-plates, the waist-band, the covers for the attaching-plates, secured to the waist-band, and the continuously-coiled springs, forming the frame-work of the bustle, carried by the plates, substantially as set forth. 85

4. A bustle comprising the attaching-plates, the coiled transverse springs, and the coiled longitudinal springs connecting the transverse springs, substantially as specified. 90

5. In a bustle, the transverse coiled springs, the attaching-plates to which the transverse springs are connected, and the longitudinal spring engaging the transverse springs and the body-wire C below the springs, as set forth. 95

6. A bustle comprising the attaching-plates, the coiled transverse springs carried by said plates, and the main coiled longitudinal spring having its ends secured to the attaching-plates, and being carried inward from said plates at an angle to the transverse springs and then downward, its middle portion depending below the lowest transverse spring to form a loop, as at a^6 , as set forth. 105

7. A bustle comprising the attaching-plates having a series of projecting arms, the coiled transverse springs, and the coiled longitudinal springs connecting the same, the said transverse springs having their ends coiled around the projecting arms of the attaching-plates, substantially as specified. 110

8. A bustle comprising the attaching-plates, the continuously-coiled spring bustle-frame carried by said plates, and the body-wire secured to said plates and projecting therefrom in the line of the bustle-frame, but below and separate from the same, substantially as set forth. 115

In testimony that I claim the foregoing as my own I have hereto affixed my signature in presence of two witnesses.

DANIEL OSCAR FOSGATE.
